UNITED STATES PATENT OFFICE.

SAMUEL SHAFER, JR., OF MILWAUKEE, WISCONSIN, ASSIGNOR TO CHAIN BELT COMPANY, OF MILWAUKEE, WISCONSIN, A CORPORATION OF WISCONSIN.

OPERATING MECHANISM FOR CHUTES.

1,415,410.

Specification of Letters Patent.

Patented May 9, 1922.

Application filed January 7, 1921. Serial No. 435,661.

To all whom it may concern:

Be it known that I, SAMUEL SHAFER, Jr., a citizen of the United States, residing at Milwaukee, in the county of Milwaukee and 5 State of Wisconsin, have invented certain new and useful Improvements in Operating Mechanism for Chutes, of which the following is a specification.

My invention relates to a motor driven, as 10 distinguished from a manually operated, mechanism for operating a chute through which material is delivered,—an example of which type of power driven chute is illustrated in U. S. Letters Patent #1,230,731 15 to C. W. Levalley.

It has for its object to simplify and improve mechanism of this kind.

In the accompanying drawings:—

Figure 1 is a side view of apparatus embodying my invention devised for operating the discharge chute of a concrete mixing machine.

Fig. 2 is a rear elevation of the same apparatus.

In the accompanying drawings A designates a rotated mixing drum of a concrete mixing machine, and B the discharge chute thereof. The chute represented in the drawings is of the form represented in Patent 20 #1,243,614 to Levalley and consists of an inner section b and an outer section b', these being united by a pivot d. The invention, however, is applicable to other forms of chute whether used for delivering material 25 from or to a receptacle, such as the drum A. The chute is supported by arms C fixed to a shaft 10 that extends across the machine at the rear of the drum and preferably above the discharge opening a therein, and is supported in any suitable manner.

3 indicates a power shaft, which may be the shaft from which the drum is rotated and which therefore turns whenever the machine is in operation. It carries a pair of bevel wheels 1, 2, loose upon the shaft and in mesh with a bevel wheel 4 on a shaft 5. The wheels 1 and 2 engage with diametrically opposite portions of the driven wheel 4 so that the latter is turned in one direction 45 or the other accordingly as the wheel 1 or 2 is at the moment connected with the power shaft 3. To effect this connection a clutch of usual construction is employed, the shift-

ing member of which, designated 11, is splined to the power shaft so as to turn therewith, and yet be free to be shifted into engagement with either of the wheels 1 or 2, or to occupy a neutral position between them. The shaft 3 is parallel with the axis of rotation of the drum A and the shaft 5 is 55 at right angles thereto. At the outer end of the shaft 5 is a bevel wheel 6 in mesh with a bevel pinion 7 secured to a downwardly extending shaft 8 which carries at its lower end a worm 19. This worm is in engagement with a worm wheel 9, through which it drives the shaft 10 carrying the chute B.

In the operation of a concrete mixing machine the chute is maintained at rest in one or the other of two positions, one, represented in dotted lines in Fig. 1, being the position occupied when material is being discharged from the mixing drum, and the other, represented in full lines in the same view, the position occupied while the chute 75 is inactive and during the time the batch of concrete is being mixed but not discharged. The worm wheel 9 is loose upon the shaft 10, but is connected therewith through an arm 21 secured fast to the shaft, and a breaker or shear pin 12, inserted in openings formed respectively in the arm 21 and wheel 9 and arranged to be brought into alignment with each other. The reason for thus connecting the driven, chute-carrying shaft 10 80 with the power will be later stated.

13 indicates a crank arm keyed to the shaft 10. It carries at its outer end a stud or projection 20 adapted to enter and to move along a slot 14 formed in a link 15 90 that is pivotally connected with the operating lever 16 for the shifting member 11 of the clutch on the power shaft. This lever is supported by a shaft 22, parallel with the shaft 5 and preferably arranged above it, 95 carrying the yoke 23 by which the clutch member 11 is shifted. At the opposite ends of the slot 14 in the link 15 are adjusting screws 17 and 18, adapted, by their positions, to determine the length of the slot, and accordingly the distance the projection 20 of the crank arm 13 is allowed to move relative to the link 15 and without imparting motion thereto. The clutch shifting lever 16 is adapted to be operated manually, as well as 100 automatically.

The operation of the mechanism will now be described: It will be assumed that the chute is in its inactive position, indicated by full lines in Fig. 1, where it remains until 5 the contents of the drum A are to be discharged. When this time arrives the attendant moves the clutch lever 16 so as to engage the gear 1 with the power shaft. This causes the shaft 10 to be turned and the 10 chute brought to the position indicated by dotted lines in Fig. 1. As the shaft 10 is turned the crank arm 13 turns with it, and as it moves the projection 20 moves along the slot 14 in the link 15 until it comes into engagement with the end of the adjusting screw 17. This engagement arrests the relative movement of the projection 20, as to the link, and insures that further movement 15 of the shaft 10 and crank arm 13 shall be transmitted to the clutch shifting lever 16, bringing the movable clutch member 11 into neutral position at the moment the discharge chute reaches the position it is to occupy 20 for discharge purposes. If, for any reason, 25 the clutch should not be operated as just described, and the driving connection be maintained so as to cause the discharge chute to overtravel, bringing it into engagement with the mixing drum or with some 30 fixed part of the apparatus, the shear pin 12, through which the force to move the chute is transmitted, would yield and the shaft 10 would remain inoperative even though the worm wheel 9 would continue in rotation. 35 When the chute is to be moved back to inoperative position the attendant moves the shifting lever 16 so as to connect the chute-moving mechanism with the power shaft through the wheel 2, and the reverse movements to those that have been described take 40 place. As, during such movements, the projection 20 of the crank arm 13 reaches the inner end of the slot 14 and comes into engagement with the adjusting screw 18, it 45 shifts the clutch to neutral position, arresting the chute in the desired outer or inoperative position.

It will be seen that the mechanism described provides for automatically arresting 50 the chute-driving mechanism when the chute has come to one or the other of the positions in which it is to remain at rest, and that there are provided adjustable means by which these positions of rest can be accurately determined, varied, and regulated.

The crank arm 13 and slotted link 15 constitute a lost-motion connection intermediate between the power shaft and the chute-carrying shaft. The adjustable screws 17 60 and 18 constitute means by which the amount of lost motion in this connection may be controlled.

The gearing, between the power shaft 3 and the chute-carrying shaft 10 may be protected by a suitable casing or housing.

It will be seen that the shaft 8 and the gears which it carries constitute a train of gearing that is intermediate between the reversing gearing on the power shaft 3 and the rock shaft that carries the chute. This 70 arrangement of gearing has been devised with especial reference to using the invention in connection with a concrete mixer, as represented in the drawings, where it is desirable that the power shaft 3 shall be along 75 side of and close to the mixing drum. This in turn makes it necessary that the power shaft and the rock shaft carrying the discharge chute shall be in different vertical planes. The arrangement shown connects 80 these two shafts in such way that the power shaft and the rock shaft may respectively occupy positions most advantageous for their use in a concrete mixing machine and yet make the entire mechanism compact so 85 that it may be enclosed by a single casing or housing of small size and located close to the mixing drum.

What I claim is:

1. A chute, a rock shaft by which the chute 90 is supported, a power shaft, reversing gearing and a clutch associated with the power shaft, an intermediate shaft between the said reversing gearing and the rock shaft through which motion is communicated from the 95 power shaft to the rock shaft, in one direction or the other as the clutch is adjusted, and means for automatically moving the clutch to neutral position when the chute arrives at the desired limit of movement. 100

2. A chute, power-driven mechanism for intermittently oscillating it, including a clutch adapted to connect the chute-operating mechanism with the source of power so as to move the chute in one direction or the other, or to occupy a neutral position with the chute disconnected from the source of power and at rest, means for automatically moving the clutch to neutral position when the chute arrives at the desired limit of 110 movement, and means for adjusting the time at which such automatic means will operate, whereby the position at which the chute is arrested may be regulated at will.

3. A chute, a shaft supporting it, a power- 115 driven mechanism for intermittently oscillating the shaft and moving the chute, including a clutch, an arm connected with the shaft and movable therewith, and means operated by the said arm for shifting the clutch 120 to neutral position when the shaft has been turned to bring the chute to the desired position, including a lost-motion connection having an abutment, with which the arm engages to move the clutch. 125

4. A chute, a shaft supporting it, power- driven mechanism for intermittently oscillating the shaft and moving the chute, including a clutch, a lever for shifting the clutch, an arm connected with the chute-sup- 130

porting shaft and movable therewith, and adjustable means operated by the said arm for moving the lever to actuate the clutch.

5. A chute, a shaft supporting it, power-driven mechanism for intermittently oscillating the shaft and moving the chute, including a clutch, a lever for shifting the chute, a crank arm connected with the chute-supporting shaft, and a lost-motion connection between the said arm and the clutch-shifting lever arranged to move the lever to shift the clutch to neutral position as the shaft is oscillated to bring the chute to the desired positions at which it is to come to rest.

6. A chute, a shaft supporting it, power-driven mechanism for intermittently oscillating the shaft and the chute, including a clutch, a lever adapted to be manually operated for shifting the clutch to connect the chute-carrying shaft with the source of power to cause it to be turned in one direction or the other, a crank arm carried by the shaft, a slotted link connected with the clutch-shifting lever, the free end of the crank arm being movable in the slot of the said link, and adjustable screws at the ends of the slot with which the crank arm comes

into engagement as the shaft has been turned so as to bring the chute to the position at which it is to be arrested.

7. A chute, a shaft supporting it, power-driven mechanism for intermittently oscillating the shaft and moving the chute, including a clutch, means for automatically moving the clutch to disconnect the chute-carrying shaft from the source of power when the chute arrives at the desired limit of movement, and a shear pin in the driving connection of the chute-carrying shaft arranged to break if the automatic means for shifting the clutch to neutral position fails to operate and the chute be moved into engagement with some obstructing object.

8. A chute and a shaft supporting it, power-driven mechanism for intermittently oscillating the shaft, including a clutch, and a breakable pin adapted to yield should the shaft and chute be moved beyond the desired limits, an arm connected with the shaft, and means operated by the arm for shifting the clutch to neutral position, with the chute and supporting shaft disconnected from the source of power when the chute comes to the position at which it is to be arrested.

SAMUEL SHAFFER, JR.
